UNITED STATES PATENT OFFICE.

HAROLD J. BELL, OF GLOUCESTER CITY, NEW JERSEY, ASSIGNOR TO THE WELSBACH INCANDESCENT GAS LIGHT COMPANY, OF NEW JERSEY.

GAS-GOVERNOR.

SPECIFICATION forming part of Letters Patent No. 400,173, dated March 26, 1889.

Application filed July 2, 1888. Serial No. 278,736. (No model.)

To all whom it may concern:

Be it known that I, HAROLD J. BELL, a citizen of the United States, residing at Gloucester City, in the county of Camden and State of New Jersey, have invented new and useful Improvements in Gas-Governors, of which the following is a specification.

My invention consists in a gas-governor or gas-regulating burner of the construction hereinafter described and claimed.

In the annexed drawings, Figure 1 is a vertical section of a portion of a gas-regulating burner illustrating my invention. Fig. 2 is an elevation of the base and inner portion of the gas-governing device. Fig. 3 is a horizontal section on the line $x-x$ of Fig. 2. Fig. 4 is a perspective of the float-valve.

The numeral 1 designates the base of the gas-governing device, and 2 the shell which forms the casing and supports the burner. The base 1 is formed with an internally-screw-threaded neck, 3, for attachment to a gas-fixture, and with an externally-screw-threaded shoulder, 4, that engages internal threads in the lower end of the shell or casing.

Above the neck 3, and communicating therewith, is a tubular stem, 5, having a series of lateral gas-exits, 6, that are located in an annular countersink, 7, about midway the height of said stem. The tubular stem 5 is closed at the top.

Surrounding the tubular stem 5 is a tubular valve, 8, the lower end of which normally rests on the flat upper surface of the base. The upper portion of this tubular valve is provided with lateral openings 9, that correspond with the lateral gas-exits 6 of the tubular stem 5, and immediately above these openings 9 is a disk-float, 10, that is attached to or formed on the valve. It will be seen that both ends of the tubular valve 8 are open. The periphery of the disk-float 10 approaches but does not touch the vertical wall of the shell 2, an annular gas-passage, 11, being left between the disk and the casing or shell. This casing or shell is cylindrical in form and has a nipple or pillar, 12, for the attachment of any suitable burner. The gas that enters the tubular stem 5 passes out through the openings 6 and 9 into the shell 2 beneath the

disk-float 10, and then upward around the periphery of said float to the upper part of the shell or casing and onto the burner. If the pressure of gas in the shell 2 is very great, it will cause the float 10 and valve 8 to rise, thereby diminishing the flow of gas at the openings 6 and 9 and regulating the pressure at the burner.

It will be observed that no matter what lateral position the tube 8 may assume on the tubular stem 5 the annular countersink or groove 7, formed in said stem, will prevent any obstruction to the flow of gas through the openings 6 and 9, which might otherwise occur by a partial rotation of the tubular valve.

In another application, Serial No. 278,735, of even date herewith, I have described and claimed a gas-regulator having a tubular perforated stem closed at its upper end and surrounded by a tubular open-ended valve provided with lateral perforations and carrying a disk-float that operates in an annular open-top chamber or cup surrounding the tubular perforated stem, a gas-passage being provided through the lower part of said cup, which gas-passage is controlled by an adjusting-screw located in the base of the regulator. In my present invention the cup and adjusting-screw are dispensed with, and the disk-float 10 is fitted with sufficient looseness in its surrounding shell or case to afford an annular passage, 11, for the exit of gas to the burner.

I am aware that a gas-valve has heretofore comprised a laterally-perforated tube closed at its upper end by a disk-float; but this I do not claim.

In applications Serial Nos. 278,732, 278,733, and 278,737, of even date herewith, I have shown gas-regulators comprising a two-part shell having an internal tubular laterally-perforated stem closed at its upper end and provided with a guide for a flaring conical float, which operates in a cup surrounding the base of said tubular stem, the float being provided with an internal tubular valve to control the gas-openings of the stem. In each of the above-mentioned applications the float-valve is shown with a lower flaring end, which fits somewhat closely in the surrounding cup without binding therein, and a gas-passage to

the burner is afforded through an opening in the bottom of the cup, which is controlled by an adjusting-screw in the base of the regulator. In an application Serial No. 278,734, of 5 even date herewith, I have shown a construction in which the controllable gas-passage through the bottom of the cup is omitted, and the conical float-valve is fitted loosely in the cup in such a manner as to provide an annular gas-passage between the cup and valve. By my present invention I dispense with the cup and the conical valve-float, and I attach 10 to the tubular valve a disk-float, which fits loosely within the upper part of the regulator-shell, thereby affording an annular gas-passage between said disk and shell. This construction differs from that described in my application Serial No. 278,735 in the particulars hereinbefore explained.

15 I would have it understood that I do not 20

broadly claim a gas-governor having a tubular perforated valve provided with a disk-float; but

What I claim as my invention is—

In a gas-governor or gas-regulating burner, 25 the combination of the base 1, having a tubular stem, 5, closed at the top and provided with lateral gas-exits 6, located in an annular countersink, 7, the upper shell, 2, and the tubular valve 8, having lateral openings 9 30 and provided with a disk-float, 10, fitting loosely in the surrounding shell, an annular gas-passage, 11, being provided between said float and shell, substantially as described.

In testimony whereof I affix my signature in 35 presence of two witnesses.

H. J. BELL.
